UNITED STATES PATENT OFFICE.

JAMES ANDREWS AND GUSTAV LINDENTHAL, OF ALLEGHENY, PENNSYLVANIA.

CONSTRUCTION OF LIGHT-HOUSES.

SPECIFICATION forming part of Letters Patent No. 438,976, dated October 21, 1890.

Application filed July 5, 1890. Serial No. 357,796. (No model.)

To all whom it may concern:

Be it known that we, JAMES ANDREWS and GUSTAV LINDENTHAL, both of Allegheny, in the county of Allegheny and State of Pennsylvania, have invented new and useful Improvements in Light-Houses and Similar Structures, of which the following is a specification, reference being had to the annexed drawings, forming a part thereof, in which—

10 Figure 1 is a vertical transverse section of a light-house constructed according to our improvement. Fig. 2 is a horizontal section taken on line $x-x$ in Fig. 1, and Fig. 3 is a horizontal section taken on line $y-y$ in Fig. 1.

15 Similar letters of reference indicate corresponding parts in all the views.

The object of our invention is to construct a light-house or analogous structure with a part of the foundation and superstructure 20 formed integrally of a single tube or shaft.

Our invention consists in the construction and arrangement of parts hereinafter described and claimed.

The inner shell A of the foundation B is 25 connected with the outer casing C by means of radial arms a and diagonal braces b , the said radial arms and braces forming series of trusses for supporting the inner shell against the vertical thrust of the upper portion D of 30 the shell, which projects upwardly beyond the foundation B. The space between the inner shell A and the outer casing C of the foundation is filled with concrete. The outer casing C extends a short distance below the

lower edge of the inner shell and is connected 35 with the said inner shell by an annular bottom plate E.

The upper portion D of the shell A may serve, without any additions or modifications except the lantern F at the top, as the light-house; but we prefer to build upon the foundation B, around the upper portion of the shell, a masonry wall G, which, together with the upper portion D of the shell A, will form the superstructure of the light-house. The 40 said wall G is secured to the casing C by means of radial bolts c , as shown in Fig. 3.

It is obvious that a structure of this character is better able to resist the lateral pressure of the wind and the impact of the waves 45 than a light-house constructed of masonry and secured to its foundation by means of bolts.

Having thus described our invention, what we claim as new, and desire to secure by Letters Patent, is—

In a light-house or analogous structure, the combination of a foundation and a superstructure formed of an inner shell prolonged above the foundation, an outer casing, a filling of concrete, and a protecting-wall of masonry laid against the prolongation of the inner shell, substantially as specified.

JAMES ANDREWS.

GUSTAV LINDENTHAL.
